UNITED STATES PATENT OFFICE.

LOUIS HIRSCH, OF MESILLA PARK, NEW MEXICO.

SPARK PLUG.

Application filed July 26, 1924. Serial No. 728,412.

To all whom it may concern:

Be it known that I, LOUIS HIRSCH, a citizen of the United States, and a resident of Mesilla Park, in the county of Doña Ana 5 and State of New Mexico, have invented a new and Improved Spark Plug, of which the following is a full, clear, and exact description.

This invention relates to improvements in 10 spark plugs, an object of the invention being to provide an improved construction for plug wherein a pair of sparks is provided at the inner end of the plug so as to insure a more complete combustion and therefore 15 greater power with more speed and less carbon accumulation.

A further object is to provide a spark plug with a pair of electrodes having terminals spaced apart, with an isolated conductor interposed between them and spaced from both, whereby the current is caused to jump from one terminal to the conductor and from the latter to the other terminal thereby insuring a plurality of sparks simultaneously.

A further object is to provide a plug of this character which may be connected in any electric circuit, either in multiple arc or series and arranged to suit the trade.

With these and other objects in view, the invention consists in certain novel features of construction and combinations and arrangements of parts which will be more fully hereinafter described and pointed out 30 in the claims.

In the accompanying drawings—

Figure 1 is a view in longitudinal section illustrating my improved spark plug;

Figure 2 is a view in transverse section on 40 the line 2—2 of Figure 1;

Figure 3 is a view in transverse section on the line 3—3 of Figure 1;

Figure 4 is a plan view of the gasket or washer 9.

1 represents the casing of my improved spark plug having a screw-threaded inner end 2 for attachment to the engine cylinder and provided with an internal annular shoulder 3 and an internally screw-threaded outer end 4. 5 represents the core of the plug, which is of porcelain or any other suitable insulating material, and this core 5 is made with an enlargement 6 which is engaged by a nut 7 screwed into the threaded outer end of the casing 1, with a washer 55

or gasket 8 interposed between the nut 7 and the enlargement 6, and a second washer or gasket 9 interposed between the enlargement 6 and the shoulder 3.

The core 5 is of general cylindrical form 60 throughout its upper or outer portion but its lower or inner portion is of general elliptical shape so that the washer 9 has an elliptical opening 10 to accommodate the lower end of the core. The inner face of 65 the casing 1 is recessed in opposite sides, as shown at 11, to accommodate the elliptically-shaped end of the core, and said core is made with a pair of longitudinal bores 12 receiving electrodes 13 therein. Binding 70 posts 14 are provided on the outer ends of the electrodes 13 and the inner ends of the electrodes are bent toward each other, forming terminals 15. An electric conductor 16, 75 which may constitute an ordinary piece of wire, is secured in the lower end of the core 5 between the terminals 15 and spaced from both terminals so that the electric current is compelled to jump from one terminal 15 to the conductor 16 and from the latter to 80 the other terminal 15, whereby a pair of sparks is formed to insure ignition of the charge and give improved results. The inner end of the core 5 where the electrodes pass therethrough is preferably recessed, as 85 shown at 17, so as to prevent an accumulation of carbon to interfere with the proper functioning of the plug.

Various slight changes and alterations 90 might be made in the general form of the parts described without departing from my invention, and hence I do not limit myself to the precise details set forth but consider myself at liberty to make such slight changes and alterations as fairly fall within the spirit and scope of the appended claim.

I claim:

A spark plug, including a casing, a core 100 in the casing, a pair of electrodes in the core, an isolated electric conductor located at the inner end of the core and spaced from the terminals of the electrodes, said core at its inner end being substantially elliptical in cross section, the shell or casing being substantially circular in cross section and having recesses in its opposite walls whereby the surface of the shell or casing is spaced 105 from the edges of the core.

LOUIS HIRSCH.
